UNITED STATES PATENT OFFICE.

JAMES M. McCONNELL, OF NICKELSVILLE, VIRGINIA.

RAILWAY-RAIL JOINT.

No. 902,434.

Specification of Letters Patent.

Patented Oct. 27, 1908.

Application filed April 7, 1908. Serial No. 425,778.

To all whom it may concern:

Be it known that I, JAMES M. McCONNELL, a citizen of the United States of America, residing at Nickelsville, in the county of Scott and State of Virginia, have invented new and useful Improvements in Railway-Rail Joints, of which the following is a specification.

This invention relates to railway rail joints, and one of the principal objects of the same is to provide a strong, durable and efficient rail joint which will not require the use of fish plates or bolts.

Another object is to provide a rail joint which can be quickly connected and which will not require skilled laborers to lay the track.

These and other objects may be attained by means of the construction illustrated in the accompanying drawing, in which,—

Figure 1 is a plan view of a rail joint made in accordance with my invention, the two parts being connected. Fig. 2 is a perspective view of the two members disconnected. Fig. 3 is a longitudinal sectional view of the same. Fig. 4 is a vertical section through the joint.

Referring to the drawing for a more specific description of my invention, the numeral 1 designates the end of one of the rails, and 2 is the end of the other rail. The rail is provided with a projecting member 3 having oppositely beveled sides 4 and terminating in a rounded head portion 5. On opposite sides of the member 3 slots or recesses 6 are provided, said slots being formed in the enlarged portion 7 of the joint. The base flange 8 of this member of the joint terminates at the end of the enlarged portion 7, as shown in Fig. 2. The other member of the joint comprises an enlarged portion 8^a having a vertical slot or recess 9 for the projecting member 3, said slot terminating in an oval or elliptical recess 10 for the rounded head 5 of the member 3. This elliptical recess 10 permits a certain amount of move-

ment of the member 3 to compensate for the contraction and expansion by cold and heat and to give and take by the action of the rolling stock in passing over the joint. The 50 enlargement 8^a is provided with two forwardly extending lugs 11 which fit in the slots 6 in the member 1. Owing to the head 5 being greater in transverse area than the recess 10 in the member 2, the rails cannot 55 separate in a longitudinal direction.

From the foregoing it will be obvious that my rail joint is strong and durable, will effectually prevent spreading or creeping of the rails and that fish plates and bolts are 60 not required to hold the same in place.

Having thus described the invention, what is claimed as new, is:—

1. A rail joint comprising one rail having a projecting member, slots at the sides of 65 said member, a rail end having a recess therein, and projecting lugs which fit the slots at the side of the projecting member.

2. A rail joint comprising one rail having a projecting member provided with oppositely beveled sides, a head of substantially circular form, oppositely beveled sides, a rail provided with a central recess for the extension member, and projecting lugs to fit the slots at the sides of said member and a recess 75 of oval formation to receive the rounded head of the other member.

3. A rail joint comprising a rail having a projecting member, slots at opposite sides of 80 said member, a base flange, said member having oppositely beveled sides and a rounded head, in combination with a rail end provided with a slot and an elliptical recess for the head of the other member, forwardly extending lugs to fit the slots of the other 85 member, and a rail flange.

In testimony whereof I affix my signature in presence of two witnesses.

JAMES M. McCONNELL.
